(57) **CLAIM**

We claim the ornamental design for an affixable and removable clip, as shown and described.

DESCRIPTION

FIG. 1 is a front left perspective view of an affixable and removable clip showing our new design;

FIG. 2 is a front right perspective view thereof;

FIG. 3 is a top plan view thereof;

FIG. 4 is a bottom plan view thereof;

FIG. 5 is a left side view thereof;

FIG. 6 is a right side view thereof;

FIG. 7 is a front view thereof;

FIG. 8 is a rear view thereof;

FIG. 9 is a front left perspective view in an exploded format;

FIG. 10 is a perspective view of the affixable and removable clip of FIG. 1 in an environment of use; and,

FIG. 11 is another perspective view of the affixable and removable clip of FIG. 1 in an environment of use.

The broken lines in FIGS. 10 and 11 show environment of the affixable and removable clip that form no part of the claimed design.

1 Claim, 5 Drawing Sheets
